METAL SHEET

Jack H. Wright, Chicago, Ill.

Application September 27, 1952, Serial No. 21,610

Term of patent 7 years

(Cl. D54—7)

To all whom it may concern:

Be it known that I, Jack H. Wright, a citizen of the United States, residing at Chicago, State of Illinois, have invented a new, original, and ornamental Design for a Metal Sheet, of which the following is a specification, reference being had to the accompanying drawing, forming a part hereof.

Fig. 1 is a front elevational view of a metal sheet, showing my new design;

Fig. 2 is a side elevational view;

Fig. 3 is an end elevational view; and

Fig. 4 is an enlarged cross sectional view taken along the line 4—4 of Fig. 1.

The portion of the metal sheet shown in broken lines in Figures 1 and 2 is merely a repeat of the portion shown in full lines.

I claim:

The ornamental design for a metal sheet, as shown and described.

JACK H. WRIGHT.
